OSCILLATION GENERATOR CONTROL
CIRCUITLouis A. King, Haddonfield, N. J., assignor to
Radio Corporation of America, a corporation
of Delaware

Application October 3, 1945, Serial No. 620,151

3 Claims. (Cl. 250—36)

1

This invention relates to a high frequency heating system, and particularly to the power generator circuit.

The present invention provides an electron discharge device induction heating system having among its features, a motor-controlled variable grid resistor for controlling the output power over a limited range, a bias rectifier arrangement including a relay for opening the grid circuit to stop oscillation and immediately applying a fixed holding bias to the grid to prevent intermittent oscillation, and a protective discharge gap to protect the variable grid resistor and bias supply from excessive grid circuit voltage due to possible flash-arcs in the oscillator tube.

A more detailed description of the invention follows in conjunction with a drawing whose single figure schematically illustrates the essential circuit elements of the power generator of the invention used in an induction heating system.

Referring to the drawing, there is shown an induction heating system comprising a vacuum tube 10 having its electrodes coupled to an oscillatory circuit 12 to form a Hartley oscillator. The anode of the tube is connected via blocking condenser 11 to one terminal of the oscillatory circuit, while the grid is connected to the other terminal via blocking condensers 13. The concentric cables 9, 9 connecting the oscillatory circuit to the vacuum tube 10 are a radio frequency high voltage type and enable the applicator unit to be located at some distance (50 ft. for example) from the tube 10.

The oscillatory circuit comprises the primary winding of an oil-filled radio frequency current transformer T and a gas filled fixed capacitor 15 connected in shunt to the primary winding. Several turns on the primary winding are connected to different terminals of a rotary tap switch 14 whose rotatable arm is connected to ground. This switch serves as a feed back or excitation control for the oscillator.

The secondary winding of transformer T is a single turn which is directly connected to an appropriate applicator circuit, for example, a single high current low impedance loop 40 shaped to follow the contour of the metallic object to be heated.

The anode of the tube 10 is supplied with positive polarizing potential from a source +B via an inductance coil 16. The filament of the tube 10 is supplied with suitable heating current from an alternating current supply over transformers 17, 18 and 19 having their primary windings con-

nected in parallel relation and their secondary windings also connected in parallel relation. These three filament transformers have been employed for weight considerations, and it should be understood that, if desired, they can be replaced by a single transformer. Reactors 20, 21 and 22 are provided in series with the primary windings of these filament transformers in order to limit the filament starting current to 150% of normal running current.

In circuit with the grid of tube 10 is an inductor 23 in series with a resistor 24 and a potentiometer 25. The tap on potentiometer 25 is linked to the shaft of a motor M which is controlled from a switch (not shown) on a panel located at the applicator unit which is somewhat removed from the tube 10 and associated elements. This rheostat 25 enables the operator to control the power output over a limited range, let us say 10%. An indication of the power output is given on the output meter 1 in circuit with the secondary winding of transformer T. Thus, if the rated power output of the generator is 75 kw., an adjustment of the rheostat 25 which will introduce its greatest amount of resistance may reduce the power output to, let us say 68 kw. Further reduction in power output may be obtained by reducing the anode voltage by means of reduced voltage taps on the main rectifier anode transformer (not shown).

In order to supply bias to the tube 10 for different operating conditions, there is provided in circuit with the grid a bias rectifier arrangement which includes a voltage step-up transformer 26, a resistor 27, and a dry disc rectifier 28. The contacts 1 and 2 of relay 29 are enclosed in an evacuated envelope 30. The armature within envelope 30 is magnetically operated by the relay winding. This relay 29 is connected to a suitable control circuit via leads 31 for starting or stopping oscillations. This control circuit may comprise a suitable interval timer and/or start and stop manually operated switches, or limit switches associated with the travel of the work.

When the armature of relay 29 engages contact 2 (normal position) there is supplied to the grid circuit (via resistor 27) a fixed bias supply which prevents the occurrence of intermittent oscillation ("motorboating") of tube 10 due to the large R.-C. time constant of the grid circuit when in this position since resistor 27 is large in resistive value. When the armature engages contact 1, the fixed bias supply is disconnected from the grid, and the grid circuit is set up to enable the production of oscillations by tube 10.

55

by virtue of a grid return circuit which includes lead 41, ammeter A, winding of overcurrent relay 32, lead 33 and the center tap of filament transformer 17. When the armature moves again to engage contact 2, the grid current is interrupted due to a large self bias produced by the increasingly high resistance between the relay contacts during the parting stroke from contact 1 to contact 2. If some fixed bias be not then applied, "motorboating" will occur at a rate determined by the effective R.-C. time constant of the grid circuit.

Past experience indicates that high vacuum high voltage power tubes are subject to flash-arcs which usually occur between anode and grid or cathode. These high resistance arc discharges, if of sufficient energy, can cause sufficient ionization for a low resistance power arc to follow. In the event of such an occurrence between grid and anode, the grid will go to anode potential thus subjecting all elements in the grid circuit to high voltages which will puncture the normal insulation of these elements. In view of the possibility of such an occurrence, the protective gap 34 is employed to effectively ground all elements of the grid circuit from the junction of resistor 24 and rheostat 25 to ground if the grid circuit voltage exceeds a prescribed safe value. This gas filled protective gap may, for example, be designed to breakdown at 1200 volts or 2200 volts, depending upon the insulation level of the grid circuit.

The invention was designed particularly for use with a 400 kc. Hartley oscillator giving a power output of 75 kilowatts. In this design, tube 10 was an RCA type 9C21 water cooled device to whose anode should be supplied 17,000 volts direct current (positive). The resistor 24 in the grid circuit was 1800 ohms, while the rheostat 25 had a range from zero to 2000 ohms, depending upon its variable position. Obviously, the features of the invention are not limited to these details since different circuit elements requiring different constants and voltage values can be used, depending upon the results to be achieved.

In order not to detract from the essential details of the invention, no illustration has been made of the water cooling equipment for the oscillator tube which includes a fluid circulating pump, heat exchanger, fluid storage tank, ceramic insulating coils, and other elements mounted in the oscillator tube unit, although it should be understood that this apparatus is customarily employed with high frequency heating systems.

The term "ground" used in the appended claims is deemed to include any point or surface of zero potential for D. C. or alternating current.

What is claimed is:

1. A high frequency heating system comprising an electronic power generator having a high vacuum high voltage power triode tube subject to flash-over, said tube including an anode and a control grid, an oscillatory circuit for said generator coupled between said anode and control grid, the control grid for said tube including a

fixed resistor, means for varying the power output from said system over a limited range, said means including a potentiometer in series with said fixed resistor, said potentiometer serving to control the power output of said generator over a limited range, a motor for operating said potentiometer, and a switch remotely located with respect to said motor for controlling said motor, and a protective circuit comprising a gap connected between ground and the junction point of said fixed resistor and potentiometer, said gap functioning to ground all elements of the grid circuit from said junction point to ground in the event of excessive grid circuit voltage.

- 15 2. A high frequency heating system comprising an electronic power generator having a high vacuum high voltage power tube subject to flash-over, said tube including a cathode, an anode and a control grid, an oscillatory circuit for said generator coupled between said anode and control grid, a fixed impedance and a potentiometer in series with said grid, a protective gap connected between ground and the junction point of said fixed impedance and potentiometer, a relay 20 having an armature magnetically controlled by a winding and a pair of contacts for alternately engaging said armature, said armature and contacts being enclosed in an evacuated envelope, a D. C. connection from said grid to said armature, a connection from one of said contacts to said cathode to enable the production of oscillations by said generator, and a source of fixed bias coupled to said other contact, said source including a resistor shunted by the series circuit 25 of a rectifier and the secondary winding of a step-up voltage transformer, the value of said bias being such as to prevent oscillations by said generator when said armature engages said last contact.
- 30 3. A high frequency heating system comprising an electronic power generator having a high vacuum high voltage power triode tube subject to flash over, said tube having a control grid circuit including a fixed resistor, means for varying the power output from said system over a limited range, said means including a potentiometer in series with said fixed resistor, said potentiometer serving to control the power output of said generator over a limited range, a motor for operating said potentiometer, and a protective circuit comprising a gap connected 35 between ground and the junction point of said fixed resistor and potentiometer, said gap functioning to ground all elements of the grid circuit from said junction point to ground in the event of excessive grid circuit voltage.
- 35 4. A high frequency heating system comprising an electronic power generator having a high vacuum high voltage power triode tube subject to flash over, said tube having a control grid circuit including a fixed resistor, means for varying the power output from said system over a limited range, said means including a potentiometer in series with said fixed resistor, said potentiometer serving to control the power output of said generator over a limited range, a motor for operating said potentiometer, and a protective circuit comprising a gap connected 40 between ground and the junction point of said fixed resistor and potentiometer, said gap functioning to ground all elements of the grid circuit from said junction point to ground in the event of excessive grid circuit voltage.
- 45 5. A high frequency heating system comprising an electronic power generator having a high vacuum high voltage power triode tube subject to flash over, said tube having a control grid circuit including a fixed resistor, means for varying the power output from said system over a limited range, said means including a potentiometer in series with said fixed resistor, said potentiometer serving to control the power output of said generator over a limited range, a motor for operating said potentiometer, and a protective circuit comprising a gap connected 50 between ground and the junction point of said fixed resistor and potentiometer, said gap functioning to ground all elements of the grid circuit from said junction point to ground in the event of excessive grid circuit voltage.
